US00D921048S

(12) **United States Design Patent** (10) Patent No.: **US D921,048 S**
(45) Date of Patent: ** Jun. 1, 2021

(54) **MODULE**

(71) Applicant: **SEMIKRON ELEKTRONIK GMBH & CO. KG**, Nuremberg (DE)

(72) Inventors: **Thomas Frank**, Lauf (DE); **Stefan Weiss**, Höchstadt (DE); **Patrick Sturm**, Nuremberg (DE); **Thomas Ziegler**, Piech (DE)

(73) Assignee: **SEMIKRON ELEKTRONIK GmbH & CO. KG**, Nuremberg (DE)

(**) Term: **15 Years**

(21) Appl. No.: **29/775,546**

(22) Filed: **Mar. 24, 2021**

Related U.S. Application Data

(62) Division of application No. 29/671,578, filed on Nov. 28, 2018.

(30) **Foreign Application Priority Data**

Jun. 4, 2018 (DE) 40 2018 100 536.3

(51) LOC (13) Cl. **15-01**

(52) U.S. Cl.

USPC **D15/5**; D13/110; D13/162

(58) **Field of Classification Search**

CLAIM

The ornamental design for a module, as shown and described.

DESCRIPTION

FIG. 1 is a front top perspective view of a module.

FIG. 2 is a top plan view thereof.

FIG. 3 is a bottom plan view thereof.

FIG. 4 is a front view thereof.

FIG. 5 is a rear view thereof.

FIG. 6 is a right side view thereof; and,

FIG. 7 is a left side view thereof.

The dash-dash broken lines depict portions of the module and form no part of the claimed design.

1 Claim, 7 Drawing Sheets
